UNITED STATES PATENT OFFICE

2,677,522

CIRCULATING AND VENTILATING ELECTRIC
FAN SUPPORTBenjamin H. Johnson, Mason, Ohio, assignor to
William W. Welch, Cincinnati, Ohio

Application January 18, 1951, Serial No. 206,631

2 Claims. (Cl. 248—236)

1

This invention relates to a circulating and ventilating electric fan.

One of the objects in developing this new fan was to provide a device which can be used in the fashion of a portable table or floor fan to circulate the air in a room, or installed in either a sliding sash or metal casement window in the fashion of a fixed window ventilating fan unit. Another object was to provide a device such as has just been described and which is made simply enough to be sold at a reasonable selling price while capable of functioning efficiently and practically in either of the types of service indicated. These objects are fulfilled by the invention disclosed hereinafter.

Generally speaking, this invention is in the form of an electric fan having a supporting system including a base having a flat bottom for resting on any flat support such as a table top or the floor, whereby the fan may be used in the same manner as any conventional electric fan. This fan base differs from the usual construction in that it has laterally spaced, outwardly extending, substantially parallel flanges arranged to extend parallel with the axis of the fan. The system further includes a shelf having a flat top constructed for supporting the fan's bottom and provided with laterally spaced, substantially parallel channels constructed for slidably receiving the flanges of the fan base. At its front end this shelf has a bottom shaped to rest on a window sill, the average window sill being usually narrower than it is possible to make a fan base for a fan of effective size. The back end of this shelf is constructed to overhang backwardly from the inside edge of the window sill. A set of depending fingers are provided for the shelf's front end, one of these fingers being shaped to engage the outside edge of a sliding sash window sill, and another of the fingers being shaped to engage the outside edge of a metal casement window sill. Means are provided for releasably connecting either one of these fingers with the shelf's front end, and an arm depends from the bottom of the shelf at a location spaced backwardly from its front end. A vise member is carried by this arm and works forwardly oppositely toward the fingers to clamp the opposite edges of a window sill therebetween.

A fan embodying these features may be sold as a unit system. The user clamps the shelf in the window sill by using the one of the fingers appropriate to the type of window involved. The fan may either be used in the usual fashion or slid into the shelf which then functions as a

2

bracket rigidly and safely installing the fan at the window so that it can function as a window ventilator or fan.

A specific example of a device embodying the foregoing is illustrated by the accompanying drawings, the various figures of which are as follows:

Figure 1 is a front view of the fan installed at a window.

10 Figure 2 is a top view of the shelf.

Figure 3 is a side view of the fan base and shelf with parts of the latter and the window sill shown cross-sectionally. In this instance, the fan is installed at a sliding sash type window.

15 Figure 4 is a top view of a portion of the finger used in the case of a sliding sash type of window.

Figure 5 is a top view of a portion of the finger used in the case of a metal casement window.

20 Figure 6 is a cross-section illustrating the use of the device in the case of a metal casement window and showing only the parts required to demonstrate this type of installation.

The illustrated device includes an electric fan unit 1 carried by a yoke 2 with the latter supported by a base 3 having a flat bottom 4. Thus, the illustrated fan may be used in the fashion of a standard circulating fan.

25 The laterally spaced, outwardly extending, substantially parallel flanges 5 are shown as being located directly at the bottom level of the base 3 but so as to not interfere with the latter's flat-bottom characteristic. In the present instance the yoke 2 is swiveled on the base 3, but if the fan is fixed relative to the base the flanges 5 preferably should extend parallel to the axis of the fan.

30 A shelf 6 has a flat top 7 constructed for supporting the bottom 4 of the fan base 3. In this instance, and also in the case of the bottom of the fan base, the flat support need not literally be a smooth plane. For example, the fan base 3 may be in the form of a pressed metal shell with its edges defining the flat bottom, and in the case of the shelf, particularly when it is made of sheet

35 metal, stiffening ribs or the like may be used, providing the overall contour is cooperatively flat with the bottom of the fan base. The side edges of the shelf 6 provide substantially parallel channels 8 constructed and arranged to slidably receive the flanges 5 of the fan's base. Either these flanges or those on the fan base may be made to depart slightly from an exact parallel relationship so that the flanges and channels can be wedged slightly to effect a more secure connection. Ordinarily, this is unnecessary, the exactly

parallel relationship having the advantage that the fan base can always be removed from the shelf with relative ease. When the shelf is made from sheet metal the flanges 8 may be conveniently bent to form from the sheet material.

The front edge of the shelf 6 is provided with a plurality of transverse elongated holes 9 and this edge is furnished with a set of depending fingers. One finger 10 is in the form of a relatively simple angle and is provided with partial punches 11 forming teeth. This finger is intended for use in the case of a sliding sash window having the usual wood surface at the front edge of the window sill into which the teeth may grip. The other finger 12 provides an upstanding extension which then bends forwardly and downwardly to provide a hook effect 13 which can hook over the metal front edge of a window sill of a metal casement window. In both instances, the finger elements are provided with a plurality of tongues 14 which fit through the holes 9 so that the finger elements may be hooked as desired to the front end of the shelf 6. The finger elements are preferably long enough to extend the complete width of the shelf.

An arm 15 depends from the bottom of the shelf 6 and non-rotatively mounts a nut 16 through which a screw 17 is threaded. This screw 17 extends toward the front end of the shelf and has a swivel block 18 facing in that direction while its other end is provided with a winged head 19. These elements cooperatively function as a vise means or member in cooperation with which every one of the fingers is used at the front edge of the shelf.

The device is shown in use in the case of a sliding sash type of window by Figure 3, while Figure 6 shows the use of the device when the finger 12 is substituted for the finger 10, this being in the case of a metal casement window application.

The fan may be merchandised as a package including all of the parts disclosed. The user can easily clamp the shelf to the window sill of either a sliding sash or metal casement window, by using the appropriate one of the fingers shown by Figures 4 and 5. The application of the shelf is simple, the proper one of the fingers being hooked into place at the front edge of the shelf and dropped over the outside edge of the window sill, the winged head 19 then being turned so that the window sill is gripped in a vise-like manner. The shelf member then extends back into the room in the form of a cantilever. In the case of a sliding sash window the teeth 11 grip the wood for a more positive application, while in the case of the metal casement window the hook-like member 13 provides a good grip.

With the shelf installed, the user may use the fan as a table or floor fan. Whenever desired, the fan may be slid into the shelf so that the fan is securely locked into position at the window where it can function as a window fan.

Practically all of the parts of this supporting system may be made from sheet metal. In the case of the finger 10, the thinness of such material avoids interference with practically all conventional types of fly screens. The finger 12 may be made to first extend horizontally forwardly and to then rise abruptly so as to pass over the 70 metal casement window sill element and with the

fingers generally conforming to the metal frame. Therefore, the usual fly screens provided for metal casement windows may be used without any difficulty when the device is applied at this type of window.

I claim:

1. Apparatus for supporting an appliance base having a substantially flat bottom surface adapted to rest on a flat support and having laterally-spaced substantially parallel flanges located substantially at the level of said bottom surface, said apparatus including a substantially flat sheet-like shelf having a substantially flat top surface adapted to support said base's bottom surface and having laterally-spaced substantially parallel channels constructed and arranged substantially at the level of said top surface to slidably receive said base's flanges, said shelf having a front end having a substantially flat bottom surface adapted to rest on a window sill and said shelf having a back end extending from said front end so as to overhang backwardly from the inside of the window sill, a depending finger for said shelf's front end and adapted to engage the outside of the window sill, means for releasably fastening said finger to said shelf so that said finger may be substituted by another finger, and clamp means on the bottom of said shelf for engaging the inside of the window sill and clamp means it between said clamp means and finger.
2. Apparatus for supporting an appliance base having a substantially flat bottom surface adapted to rest on a flat support and having laterally-spaced substantially parallel flanges located substantially at the level of said bottom surface, said apparatus including a substantially flat sheet-like shelf having a substantially flat top surface adapted to support said base's bottom surface and having laterally-spaced substantially parallel channels constructed and arranged substantially at the level of said top surface to slidably receive said base's flanges, said shelf having a front end having a substantially flat bottom surface adapted to rest on a window sill and said shelf having a back end extending from said front end so as to overhang backwardly from the inside of the window sill, a depending finger for said shelf's front end and adapted to engage the outside of the window sill, said shelf's front end having at least one hole formed therethrough and said finger having a portion fitting beneath said shelf's front end and having a forwardly pointing tongue removably inserted through said hole to connect said finger with said shelf removably so said finger may be substituted by another finger, an arm depending from said shelf's bottom at a location spaced backwardly from said shelf's front end, and a screw in screw-threaded engagement with said arm and pointing towards said shelf's front end to engage the inside of the window sill.
